UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

RAILWAY-CAR CONSTRUCTION.

Application filed October 20, 1926. Serial No. 142,919.

My invention relates to railway cars, and particularly to the structure and arrangement of passenger car bodies and their doors.

One object of my invention is to provide a passenger car structure of the center entrance type, with its entrance so arranged that passengers may be conveniently discharged upon either a low platform or a high platform.

10 Another object of my invention is to provide a car door arrangement whereby greater space is provided for the entry and exit of passengers than in the types of cars heretofore employed.

15 Another object of my invention is to provide an improved door arrangement for passenger cars.

20 A further object of my invention is to provide an improved arrangement of articulated car construction.

Still another object of my invention is to simplify and improve generally the structure and arrangement of passenger cars.

25 One form which my invention may take is shown in the accompanying drawing, wherein Figure 1 is a side elevational view, showing a portion of a two-body unit constructed in accordance with my invention;

30 Fig. 2 is a view showing the remaining portion of said unit; Fig. 3 is a view taken on the line III—III of Fig. 1; Fig. 4 is a view taken on the line IV—IV of Fig. 1; Fig. 5 is a sectional plan view, on an en-

35 larged scale, of a portion of the apparatus of Fig. 3; Fig. 6 is a view taken on the line VI—VI of Fig. 5, and Fig. 7 is a cross sectional view of a portion of the car roof, showing the abutment plate for the side entrance doors of Figs. 1 and 2.

The car unit is composed of car bodies 10 and 11 that are provided with end trucks and an intermediate truck, indicated diagrammatically at 12 and 13, respectively.

45 These trucks may be of any well known construction and serve to support the car bodies. The end trucks 12 may have the usual center pin connection with the body sections. The adjoining ends of the bodies 10 and 11 are provided with sills or plates 14 and 15, respectively, that overlap, as shown more clearly in Fig. 4, to form a passage-way between the sections. One or both of the

body sections 10 and 11 has suitable swivel

connection 16 with the truck 13, through a truck bolster (not shown). A diaphragm 17, of any well known form, is connected to the body sections 10 and 11, so as to form an enclosure through which passengers may walk when passing from one car body to the other. Suitable doors 18 are provided in the adjoining ends of the car bodies.

In order to permit of a more convenient and rapid discharge of passengers, I mount side-entrance doors 19 adjacent to the mid portion of each car body. These doors are hinged at their remote edges and swing to open position, as indicated by the dotted lines 20 of Fig. 5, when it is desired to take on or discharge passengers. In ordinary steam railway practice, a single door is employed instead of two doors 19, with the result that the permissible width of door space is greatly limited, since the inner edge of the door must not be permitted to extend, when open, to a point too near the center line of the car body, because door space must be left in the end of the car to permit access to the platform thereof.

Inside doors are represented at 21, and it will be seen that these doors can be made much wider than the end doors commonly found in railway cars, because the outer or side doors 19 do not extend inwardly a great distance when open. This is an important feature of my invention, since the passengers have greater freedom of movement, and groups thereof can be more rapidly taken on and discharged. This is a particularly advantageous feature where, as shown in the drawing, passengers in leaving the car move from each end of the car body toward its central portion. It will be seen that doors 19, as shown in Figs. 1 and 2 will be provided at each side of the car bodies.

40 A trap door 23, that is hinged at 24, in the usual manner, is provided for closing the space which would otherwise be present between the central platform 25 and the doors 19 when closed, and which serves as an extension to the platform 25 over which passengers may walk when entering or leaving the car at a station platform that is high, it being understood that the doors 19 are swung back when the train stops at a station.

If the station platform is low, the latch 26 of the trap door is moved to permit the

door to be swung upward about its pivot 24. The passengers then enter and leave the car by the steps 27.

The doors 19, when closed, abut against 5 a plate 28 (Fig. 7) that is secured to a channel iron 29 and a Z bar 30, which extend longitudinally of the car. The bar 30 supports the edge of the car roof 31, and a moisture deflecting plate 32 is interposed 10 between the outer sheet of the roof and the plate 28. Rivets 33 serve to tie the various parts together, openings 34 being provided in the inner flange of the channel 29 to permit of conveniently placing the rivets. 15 The doors 21, as indicated by dotted lines in Figs. 3 and 5 are slidably mounted in suitable guides (not shown).

I claim as my invention:

1. A railway passenger car body having 20 a platform at its mid portion, steps extending downwardly from one edge of the platform, toward one side of the car, a trap door movable into horizontal position over the steps, and vertically disposed half-door 25 sections disposed above the trap door and movable in opposite directions to permit access to the platform from a point exteriorly of the car.

2. A railway passenger car body having a 30 platform at its mid portion, steps leading downwardly and outwardly from each longitudinal edge of the platform, a trap door movable into horizontal position over each group of steps, a side entrance door mounted 35 above each of said trap doors, and means for supporting each entrance door for inward movement.

3. A railway passenger car body having a 40 platform at its mid portion, doors at each end of said platform, steps leading downwardly and outwardly from each side of the platform, a trap door movable into horizontal position above each group of steps,

a side entrance door disposed above each of the trap doors, and means for supporting 45 said entrance door for inward movement.

4. A railway passenger car body provided with downwardly and outwardly extending 50 steps, a trap door movable into horizontal position above said steps, a pair of vertically disposed, entrance doors above said trap door, and means for supporting each entrance door for inward movement.

5. A railway passenger car body provided with downwardly and outwardly extending 55 steps, a trap door movable into horizontal position above said steps, a pair of vertically disposed, independently movable, entrance doors above said trap door, the adjacent edges of said doors being movable in opposite directions, and hinges supporting the remote edges of the entrance doors.

6. A railway passenger car body provided at its mid portion with a side-entrance door, 60 means at said door for permitting discharge of passengers to a high-level station platform, and means for permitting discharge of passengers to low platforms.

7. A railway passenger car body provided with downwardly and outwardly extending 70 steps, a trap door movable into horizontal position above said steps, a pair of vertically disposed entrance doors above said trap door, and means for supporting each of 75 said doors for inward movement.

8. A railway passenger car body provided with downwardly and outwardly extending 80 steps, a trap door movable into horizontal position above said steps, a pair of vertically disposed entrance doors above said trap door, the adjacent edges of said doors being movable in opposite directions, and hinges supporting the remote edges of said doors.

In testimony whereof I the said ANDREW CHRISTIANSON have hereunto set my hand.

ANDREW CHRISTIANSON.
